CLAIM

The ornamental design for a soft cooler, as shown and described.

DESCRIPTION

FIG. 1 is a top perspective view of a soft cooler depicting a new design;

FIG. 2 is a back elevation view thereof;

FIG. 3 is a front elevation view thereof;

FIG. 4 is a right elevation view thereof;

FIG. 5 is a left elevation view thereof;

FIG. 6 top plan view thereof; and,

FIG. 7 is a bottom plan view thereof.

The long-dashed and shortest dashed broken lines at the top of the article and the broken lines representing a zipper and handle, and associated stitching, on the front of the article in the figure views represent portions of the soft cooler that form no part of the claimed design. The evenly spaced horizontal broken lines in the figures depict stitching, which does form a part of the claimed design.
